United States Patent Office.

GEORGE HALSTEAD, OF BUFFALO, NEW YORK.

Letters Patent No. 91,740, dated June 22, 1869.

IMPROVED IRON-ROOF PURLIN.

The Schedule referred to in these Letters Patent and making part of the same.

To all whom it may concern:

Be it known that I, GEORGE HALSTEAD, of the city of Buffalo, county of Erie, and State of New York, have invented certain new and useful Improvements in Iron-Roof Purlins; and I do hereby declare that the following is a full, clear, and exact description thereof, reference being had to the accompanying drawings, making a part of this specification.

The nature of my invention consists—

First, in forming the upper flange of the purlin upon one side of the web, and at an angle thereto corresponding to the pitch of the roof in which it is to be employed, so that the purlin may be applied to the rafters with the plane of its web vertical and coincident with the direction of pressure, thus securing a maximum of strength with a given area of section, a result not accomplished with the common form of purlin, in which the direction of pressure is oblique to the web.

Second, in securing the purlin to the rafter, first, by so cutting away the upper part of the web of the purlin as that its flange may overlap the flange of the rafter, and, second, extending the lower part of the web, in the form of a tenon, through a mortise cut in the web of the rafter, whereby the purlin is secured in its place both vertically and laterally.

In the accompanying drawings—

Figure I is an isometrical view of two purlins and a rafter, the purlins being slightly removed from the rafter, to show more clearly the configuration of their ends.

Figure II is an isometrical view, showing the purlins in position upon the rafter.

Figure III shows in section and elevation the same parts as in Fig. I.

Like letters refer to like parts in each of the figures.

A represents the rafter, of I-form; and

B B, the purlins, the upper flange C, of which projects from one side of the web only, and obliquely thereto, its angle being governed by the pitch of the rafter with which it is to connect.

The lower edge of the web is strengthened by a bead, d.

The ends of the purlins are notched in the web, as shown at e, to the form of the flange of rafter, so that when they are applied thereto, as in Fig. II, their up-

per flange will overlap on the upper side of the flange of the rafter, and the notched end of the web passes under said flange, and up to the web of the rafter.

A tenon, f, is formed at the end of the purlin-web, and a lozenge-shaped mortise, g, is cut through the web of the rafter, which receives said tenon when the parts are brought together, as in Fig. II.

The mortise is made wide enough to receive the tenon of two purlins applied upon opposite sides of the rafter.

By this simple means of connection, the purlin is supported against vertical strains by both overlapping flange and tenon, and is held against lateral movement on the rafter by the tenon.

No bolts or rivets are required in the connection, and no metal is taken from the flanges to weaken the rafter, and that which is taken from the web by the mortises is so near the neutral axis as not to materially effect its strength.

Ample allowance for expansion and contraction may be made by leaving proper clearance between the end of the purlin and the rafter.

By the oblique position of the purlin-flange, its web is made vertical when in position on the rafter, and as the load always acts in a vertical direction, the web is made to yield its maximum of strength.

In the common forms of purlins, the flange being at right angles to the web, causes the latter to assume an inclined position when placed upon the rafter, so that the direction of the pressure passes through it obliquely, thus greatly weakening its power to resist flexure.

Having thus described my invention,

What I claim, and desire to secure by Letters Patent, is—

1. An iron purlin for roofs, having its flange oblique to the web, and arranged, in relation to the rafter, as and for the purpose set forth.

2. The iron purlin B, constructed as described, with an overlapping flange, C, tenon f, and fitted to the rafter, substantially as described.

GEORGE HALSTEAD.
